UNITED STATES PATENT OFFICE.

EDWIN B. STIMPSON, OF BROOKLYN, E. D., NEW YORK.

DESIGN FOR AN ORNAMENTAL BORDER.

SPECIFICATION forming part of Design No. 12,057, dated December 7, 1880.

Application filed September 4, 1880. Term of patent 3½ years.

To all whom it may concern:

Be it known that I, EDWIN B. STIMPSON, a citizen of the United States, residing at Brooklyn, E. D., in the county of Kings and State of New York, have invented a new and original Design for an Ornamental Border, of which the following is the specification.

The accompanying printed illustration represents a face view of my newly-designed border.

The invention relates to a new and original design for a border, which may be stamped or otherwise cut in paper, thin sheet metal, or any other suitable fabric or material, and is designed to be used for the lining or trimming of paper boxes, bird-cages, frames, for trimming shelves, ornamenting ceilings, or any other purpose for which it may be adapted, as the judgment of the user may indicate. I propose, however, to employ it chiefly in the form of a stamped-paper border.

In the printed illustration filed herewith, A is an ornamental elongated figure consisting of two substantially-straight lines, *a a*, intersecting each other at an acute angle, and two curved lines, *a' a'*, springing from the open ends of lines *a a* and intersecting each other at a more obtuse angle. By preference I form the lines which bound this figure of rows of dots or holes punched in the material, and ornament it by a central lozenge-shaped figure, *c*, and interior lines parallel with the lines *a a*.

I employ a series of the figures just de-

scribed, placed adjacent to each other, and form points B, the bounding-lines of which terminate opposite the points of alternate figures A, the intermediate figures, A, being arranged, respectively, on lines with the central extremities of the points B.

Care heart-shaped figures arranged centrally of the points B, and D are crosses arranged within the angles formed between the intersecting straight lines which form the sharp angles of the figures A.

b b are dots or perforations situated on lines described from the centers of the bounding-lines of the point B.

I claim—

1. The herein shown design for a border, having the points B and the elongated figures A, so arranged that the point of each elongated figure A shall be opposite the intersection of the boundary-lines of the points B, and the point of the other elongated figures A shall be situated, respectively, on lines with the central extremities of said points B.

2. The design for a border having the points B, elongated figures A, and crosses D, substantially as shown.

In testimony whereof I affix my signature in presence of two witnesses.

EDWIN B. STIMPSON.
